CLAIM

I claim the ornamental design for a shoe, as shown and described.

DESCRIPTIONFIG. 1 is a front perspective view of a shoe, showing my new design;
FIG. 2 is a left side view thereof;

FIG. 3 is a rear perspective view thereof;

FIG. 4 is a front view thereof; and,

FIG. 5 is a top view thereof.

The dot-dash broken lines adjacent to the shaded areas represent boundaries of the claimed design and form no part thereof. The remainder of the broken lines show portions of the shoe that form no part of the claimed design.
